UNITED STATES PATENT OFFICE

EMIL J. BERGER, OF HATFIELD, PENNSYLVANIA, ASSIGNOR TO DEXDALE HOSIERY MILLS, OF LANSDALE, PENNSYLVANIA, A CORPORATION OF PENNSYLVANIA

DESIGN FOR HOSIERY

Application filed March 3, 1932. Serial No. 43,056. Term of patent 3½ years.

To all whom it may concern:

Be it known that I, EMIL J. BERGER, a citizen of the United States, residing at Hatfield, in the county of Montgomery and State of Pennsylvania, have invented a new, original, and ornamental Design for Hosiery, of which the following is a specification, reference being had to the accompanying drawing, forming part thereof.

In the drawing:

Fig. I is a view of a stocking showing my new design; and

Fig. II is an enlarged fragmentary view showing the texture of the fabric of the stocking.

From Fig. I, which shows my design to substantially actual scale, it will be observed that the same consists of diamond figures in staggered relation, each diamond having in its infield at the center, two substantially circular openings likewise formed by single open meshes, said openings being disposed side by side. The described characteristics of my design are well brought out in Fig. II which shows the fabric enlarged approximately four times.

I claim:

The ornamental design for hosiery, as shown and described.

EMIL J. BERGER.
